UNITED STATES PATENT OFFICE.

LUI C. VERGANO, OF BERKELEY, CALIFORNIA.

DOUBLE RATCHET FOR ROLLER SKATES.

Application filed March 5, 1924. Serial No. 697,072.

To all whom it may concern:

Be it known that I, LUI C. VERGANO, a subject of the King of Italy, residing at Berkeley, in the county of Alameda and State of California, have invented certain new and useful Improvements in Double Ratchets for Roller Skates; and I do hereby declare the following to be a full, clear, and exact description of the invention, such as will enable others skilled in the art to which it appertains to make and use the same.

My invention relates to improvements in roller skates, and its primary object is the provision of a novel attachment for skates of this character which is adapted to permit the use of the skates with the least possible exertion and which will reduce to the minimum the possibility of accidents especially during the time that a person is learning to use the skates.

A further object of the invention is the provision of an attachment for roller skates which shall embody a pair of pawls and ratchet teeth carried by the front wheels of the skate, the attachment being adapted to prevent any backward rotation of the front wheels, which shall be simple, durable and efficient, and which may be manufactured and sold at a comparatively low cost.

With the above and other objects in view, the invention consists in the construction, combination and arrangement of parts hereinafter fully described and claimed, and illustrated in the accompanying drawings, wherein:

Figure 1 is a view in side elevation of a roller skate equipped with a ratchet mechanism constructed in accordance with my invention, one of the front wheels being omitted to illustrate the application of the mechanism.

Figure 2 is a bottom plan view of the forward portion of the skate,

Figure 3 is a view in elevation of the front end of the skate,

Figure 4 is a detail view in side elevation of the pawl and pawl carrying bracket on the ratchet mechanism,

Figure 5 is a detail view in front elevation of the pawls and pawl carrying bracket,

Figure 6 is a detail view in rear elevation of the pawls and pawl carrying bracket,

Figure 7 is a sectional view taken on the vertical plane indicated by the line 7—7 of Figure 5, and

Figure 8 is a detail view in perspective of one of the pawls.

Referring to the drawings by reference numerals, 1 designates the tread plate, 2 the rear wheels and 3 the front wheels of a roller skate of the usual or any approved construction. The front wheels are mounted on an axle 4, and the axle is carried by a cylindrical bearing 5 which extends forwardly from the center of the lower end of the hanger 6. This bearing and hanger are of the usual construction and are connected to the tread plate 1 in the usual manner.

The ratchet mechanism comprises a pair 7 of pawls which cooperate with ratchet teeth 8 to prevent any backward rotation of the front wheels 3. The ratchet teeth 8 are preferably formed in the inner faces of the front wheels 3. The pawls 7 are pivotally mounted on the cross member 9 of an inverted U-shaped bracket, the side members or arms 10 of which are provided with openings 11 to receive the bearing 5. To receive the web 12 by which the bearing 5 is secured to the hanger 6 and thereby permit the application of the bracket to the bearing, the side members or arms 10 are provided with slots 13 which communicate with the openings 11 and which open out through the rear edges of the side members or arms.

The rear edges of the side members or arms 10 engage the hanger 6, and owing thereto the bracket is held against any rotary movement on the bearing 5, the bracket being held against any movement lengthwise of the bearing by the front wheels 3. The pawls 7 are pivotally mounted upon sleeves 7^a confined between plates 14 and 15, and these parts are secured together and to the cross member 9 of the bracket by the pins 16 which pass through the sleeves. The sleeves 7^a are slightly longer than the thickness of the pawls 7, and hold the plates spaced slightly from the pawls so that the latter may turn freely, the sleeves being held against rotation by the frictional contact between their ends and the plates. The pins 16 are also used to secure to the under side of the cross member 9 the angled upper end 17 of a hanger arm 18 which is positioned between the side members or arms 10 and to the lower end of which a spring is secured. This spring comprises one or more loops 19 which surround a sleeve 20 upon a pin 21 carried by the lower end of the hanger arm 18, and arms 22 which extend

upwardly and pass freely through openings 23 in the pawls 7. To retain the coil or coils 19 on the sleeve 20, and to retain the sleeve upon the pin 21, a washer 24 is secured to 5 the forward end of the pin. The outer or active ends 25 of the pawls are substantially V-shaped, and they are inclined upwardly and laterally. The ratchet teeth 8 may be readily formed in the inner sides of the 10 front wheels 3, or they may be formed in plates which may be secured in any suitable manner to the inner sides of the wheels.

To equip a skate with my improved mechanism, it is only necessary to position 15 the pawl carrying bracket upon the front axle bearing 5 of the skate, and mount upon the axle 4 two wheels provided at their inner sides with ratchet teeth. The pawl carrying bracket may be readily attached 20 to the front axle bearing 5, and when in position is held against any accidental movement by the hanger 6 and by the front wheels 3. The pawl carrying bracket occupies an upwardly and forwardly inclined 25 position, and the pawls 7 extend downwardly and forwardly and outwardly from the upper end of the bracket, and they are held in position to engage the ratchet teeth by the arms 22 of the spring.

30 While the pawls prevent any backward rotation of the front wheels they offer little or no resistance to their forward rotation. As the front wheels cannot rotate backwardly, the skate which is not on the forward stroke cannot slip, and owing thereto long distances may be covered with comparatively little fatigue, the liability of falling is reduced to the minimum, the pleasure derived from skating is greatly increased, and the art of skating may be acquired in a comparatively short time.

It should be understood that the drawings are merely illustrative and do not pretend to give exact proportions. Furthermore, the said drawings are illustrative of a preferred construction, it being my expectation that various changes and modifications may be made without departing from the spirit and scope of my invention.

50 Having thus fully described my invention what I claim and desire to secure by Letters Patent, is:

55 1. A roller skate having the front wheels thereof provided with ratchet teeth, a bracket secured to the skate between said wheels and occupying an upwardly and

forwardly inclined position, pawls pivoted to said bracket and extending downwardly and forwardly therefrom, and a spring urging the pawls into the paths of said ratchet 60 teeth.

2. A roller skate having a hanger provided with a bearing, an axle carried by said bearing, wheels mounted upon the axle and provided at their inner sides with ratchet teeth, a bracket applied to said bearing, pawls pivoted to the bracket, and a spring carried by the bracket and engaging the pawls to hold them in the paths of 65 said ratchet teeth.

70 3. A roller skate having a hanger provided with an axle bearing projecting beyond the lower end thereof, a bracket having openings to receive said bearing and contacting with said end of the hanger, an axle carried by the bearing, wheels mounted upon the axle and provided at their inner sides with ratchet teeth, pawls pivoted to 75 the bracket, and a spring carried by the bracket and urging the pawls into the path 80 of said ratchet teeth.

4. A ratchet mechanism for roller skates, including a U-shaped bracket having the side members thereof provided with openings, a hanger arm secured to the cross 85 member of the bracket, pawls pivoted to said cross member, and a spring carried by the hanger arm and engaging the pawls.

5. A ratchet mechanism for roller skates, including a bracket, plates, elements securing the plates to the bracket, pawls positioned between the plates and pivotally secured in place by said elements, sleeves carried by the pawls and receiving said elements and contacting with said plates, and a spring carried by the bracket and engaging 90 the pawls.

6. A ratchet mechanism for roller skates, including a bracket, pawls pivoted to said bracket and having inclined active ends of 100 substantially V-shape, and a spring connected to the bracket and engaging the pawls.

7. A ratchet mechanism for roller skates, including a bracket, and pawls pivotally connected to the bracket and provided with inclined active ends of substantially V-shape.

In testimony whereof I affix my signature.

LUI C. VERGANO.
